UNITED STATES PATENT OFFICE.

JAKOB KIENZLE, OF SCHWENNINGEN, GERMANY.

REPEATING CLOCK.

SPECIFICATION forming part of Letters Patent No. 708,364, dated September 2, 1902.

Application filed June 3, 1901. Serial No. 62,985. (No model.)

To all whom it may concern:

Be it known that I, JAKOB KIENZLE, a citizen of Würtemberg, residing at Schwennen-
gen, Würtemberg, Germany, have invented
5 certain new and useful Improvements in Re-
petition-Clockworks; and I do hereby declare
the following to be a full, clear, and exact
description of the invention, such as will enable
others skilled in the art to which it ap-
10 pertains to make and use the same.

This invention relates to improvements in
repeating clocks, and has for its object to sim-
plify the construction and to provide means
for setting the clock even when it is striking
15 without any danger of deterioration.

My invention will be fully understood on
reference to the annexed drawings, which
form a part hereof, and in which—

Figure 1 is a front elevation of a clock mech-
20 anism fitted with my improvements. Fig. 2 is
a plan view of the same. Fig. 3 is a side view
of the parts appearing in Fig. 2. Fig. 4 is a
detail view of the segment and the lever and
25 spring at the lower end thereof, and Fig. 5 is
a detail view of the arresting-lever and the
cam for operating the same.

The arresting and releasing lever *a*, of a
nearly semicircular form, rotates about a pin
30 *b*, fixed upon the side wall *c*, and is provided
with two pins *d* and *e*, fixed near its lowest
and highest points, respectively. In the curve
or bend of the arresting-lever is arranged a
35 snail-formed cam *f*, carrying pins *g* and *h* on
its front and rear sides, respectively. The
pin *h* by impinging against the lower edge of
the curve or bend of the arresting-lever serves
40 to raise said lever when the cam is rotating,
and thereby prevent the pin *e* from falling
into engagement with the cam and stopping
the gear. The other pin *g* during the rota-
45 tion of the cam engages the teeth of the seg-
ment *i* and advances the same. This segment
has its movement in one direction limited by
a pin *k*, fixed on the front plate or wall *c*, and
in the other direction by the pin *d* of the ar-
resting-lever.

The release of the arresting-lever is effected
by drawing down the lower arm of the repeat-

ing lever *l*, and thereby causing the upper
arm of said lever to swing outward in contact 50
with the arresting-lever, and consequently
carry the pin *e* out of engagement with the
cam *f*, so that said cam will be rotated.

In the ordinary construction of repeating
clocks the segment *i* after the release fell 55
upon the hour-snail *p*. If the clock was set
while striking, it was liable to be deteriorated
by the knocking of the hour-snail against the
pin of the segment. In the present invention
this inconvenience is overcome by a lever *q*, 60
fixed upon the axis *r* of the segment. At the
extremity *s* of this lever *q* is secured a spring
r, provided at its opposite end with a pin *r'*
passing through a notch in the end of the
lever and falling upon the hour-snail after 65
the release of the segment. The hour-snail
is beveled at its edge *p'*, so that when during
a turn of the hour-snail—as, for instance,
when the clock is being set—the said edge
pushes against the pin *r'* the said pin is 70
pressed backward, and the hour-snail passes
by without disturbing or damaging any of the
parts.

In the ordinary operation of the clock the
inner end of the releasing-lever is actuated 75
by the striking-cam at the close of the hour
or half-hour, as will be readily understood.
Should it be desired to so sound the hour be-
tween the beginning and close of these periods,
the said lever is actuated manually. 80

Having thus described my invention, what
I claim, and desire to secure by Letters Pat-
ent, is—

1. In a repeating clock, the combination
with the segment, of an arresting-lever, 85
adapted to arrest the movement of the seg-
ment, and a cam controlling the striking mech-
anism and engaging said lever.

2. In a repeating clock, the combination
with the segment, of a forked arresting-lever, 90
and a cam forming a part of the striking mech-
anism and arranged within the fork of said
lever provided on one side with a pin adapted
to engage the lever and on the other side with
a pin adapted to engage the segment, the said 95
lever being provided with a pin adapted to

engage the segment and with a second pin adapted to engage the shoulder of the said cam.

3. In a repeating clock, the combination of the segment, the repeating lever, an arresting-lever bearing on the repeating lever, and adapted to engage the segment, and a cam forming a part of the striking mechanism

and adapted to engage both the segment and the arresting-lever.

In testimony whereof I affix my signature in presence of two witnesses.

JAKOB KIENZLE.

Witnesses:

AUGUST DRAUTZ,
WALTER SCHWAEBSCH.
